UNITED STATES PATENT OFFICE.

JAMES A. HINSON, OF CHICAGO, ILLINOIS.

DRAFT-RIGGING.

SPECIFICATION forming part of Letters Patent No. 755,296, dated March 22, 1904.

Application filed June 24, 1903. Serial No. 162,859. (No model.)

To all whom it may concern:

Be it known that I, JAMES A. HINSON, of Chicago, in the county of Cook and State of Illinois, have invented certain new and useful 5 Improvements in Draft-Rigging; and I do hereby declare that the following is a full, clear, and exact description thereof, reference being had to the accompanying drawings, and to the letters of reference marked thereon, 10 which form a part of this specification.

This invention relates to improvements in draw-bar draft-rigging for car-couplers, and refers more specifically to devices located between the draw-bar and the draft-sills for 15 taking up or absorbing shocks transmitted to the draw-bar in the tractive use of the car and during the operations of coupling and also for lessening the recoil of the parts under the action of the spring or springs placed under 20 tension.

As shown in the drawings, Figure 1 is a top plan view, partially in section, of a draft-rigging embodying my invention. Fig. 2 is a longitudinal section thereof, taken on line 2 2 25 of Fig. 1. Fig. 3 is a transverse section taken on line 3 3 of Fig. 2.

As shown in the drawings, A A designate draft-sills, which are herein shown as made of flanged metal bars, C the draw-bar of the 30 coupler, and C' the yoke thereof, located between said draft-sills.

D D designate follower plates or bars, which extend transversely through the draw-bar yoke and engage at their ends inwardly-opening 35 pockets formed in draft-plates E E, which are attached to the inner faces of the draft-sills.

F F' designate inner and outer coiled expansively-acting springs which are located 40 between the upper and lower members of the draw-bar yoke and act against the follower-bars through intermediate agencies hereinafter to be described, whereby the springs act to resist in the usual manner the draft and buffering thrusts of the draw-bar and to restore 45 the parts of the draft-rigging.

In addition to the springs F F' for resisting the draft and bumping thrusts of the draw-bar I have provided auxiliary spring devices,

which are so constructed as to embody in the 50 parts thereof friction-producing devices which supplement the action of the springs to resist the buffering and draft thrusts of the draw-bar. Said springs, as herein shown, consist of two compound U-shaped springs G G', each made 55 up of a number of separate flat leaves. One of said compound springs—the spring G in the present instance—flares outwardly at its open end, while the arms of the other compound spring G' incline toward each other and fit 60 within the arms of the larger or outer spring and bear with their outer faces against the inner faces of the arms of the outer spring. The leaves which constitute each of said springs G G' are made of varying lengths, the 65 adjacent leaves of each spring being made gradually longer. In the larger spring G, or the one of which the arms thereof fit outside the other spring G', the shortest leaf is the 70 outside leaf, while the longest leaf is the inside leaf. This arrangement is reversed in making up the spring G'—that is to say, the shortest leaf of said spring is the inside leaf, while the longest leaf is the outside leaf. The inner 75 faces of the arms of the longest leaf of the outer compound spring G has close frictional bearing with the outer faces of the arms of the longest leaf of the inner spring G', whereby when the springs are closed together the friction between said leaves of the springs act 80 to resist closing movement.

The springs G G' are seated at their closed ends in curved seats formed in the inner faces of the follower-bars D, whereby said springs are held laterally in place. Said springs are 85 held vertically in place between the arms of the yoke C'. The coiled springs F F' bear at their ends against blocks f f, which are curved on their outer faces to fit the inner curved faces of the innermost leaves of the springs. 90 If desired, said blocks f may be made integral with the parts of the follower-bars in which are formed the seats for said springs, in which event the springs would be made slightly narrower relatively to the height of the draw-bar 95 yoke. Endwise movement of the draw-bar in either direction acts to close said springs G G' together and at the same time compress the

springs F F', and when the draft or buffing strain is released said springs F F' act to restore the parts of the draft-rigging to their normal or inactive position.

- 5 By reason of the outwardly-flaring form of the arms of the spring G' and the complementary inwardly-turned arrangement of the arms of the spring G', which fit between the flaring arms of the spring G, it will be seen that when
- 10 the said springs are closed together the inner spring acts as a wedge to open the outer spring, while the resistance of the outer spring acts in a manner to close the inner spring. Thus the larger and smaller springs act mutually to
- 15 resist the draft and buffing thrusts of the draw-bar. Such draft and buffing thrusts of the draw-bar are not only resisted by the resilient action of the springs G G', supplementing the action of the springs F F', before referred to, but are resisted also by the friction which is developed between the contacting faces of the inner and outer springs G G', as well as by the interacting friction developed between the several leaves of each of the
- 25 springs G G' during the opening and closing movements of said springs—that is to say, owing to the form of the springs, when the arms of said springs are moved outwardly and inwardly, respectively, due to the closing of
- 30 the springs together, the adjacent leaves of each spring shift relatively to each other, and thereby produce a friction which is exerted to resist the closing movements of the springs due to the draft and buffing strains of the draw-bar.

It is obvious that the draft-rigging herein described may be made to possess enormous resisting power, as there is ample space for adding leaves to the springs to produce the required spring strength. Moreover, by reason of the frictional contact between the two springs G G' and between the leaves or members of each spring said springs overcome largely the recoil of the parts and the injury due to such recoil.

The springs G G' may be supplemented by a spring or springs located outside of or surrounding the same—such, for instance, as shown in my prior application for United States Letters Patent, Serial No. 152,345, filed on the 13th day of April, 1903. In such suggested construction the springs G G' correspond to the wedge members shown in said prior application, but differ from said wedge members in that they are spring wedge members. Other modifications will occur to those skilled in the art, and I do not wish to be limited to the illustrated construction except as hereinafter made the subject of specific claims.

60 I claim as my invention—

1. In a draft-rigging the combination with a draw-bar and its yoke, of two springs which are closed together by the draft and buffing thrusts of the draw-bar, said springs having

inclined, coacting, frictional surfaces and each 65 comprising a plurality of leaves which are relatively shiftable when placed under stress.

2. In a draft-rigging, the combination with a draw-bar and its yoke, of two interacting wedge-shaped springs which are closed together by the drafting and buffing thrusts of the draw-bar, said springs each comprising a plurality of leaves which are relatively shiftable with respect to each other when the springs are placed under tension. 75

3. In a draft-rigging, the combination with a draw-bar and its yoke, of two U-shaped springs, one of which is made flaring at its open end to receive the arms of the other spring and means whereby said springs are 80 closed together during the buffing and draft thrusts of the draw-bar.

4. In a draft-rigging, the combination with the draw-bar and its yoke, of two U-shaped springs, one of which is made flaring at its 85 open end to receive the arms of the other spring, said springs each comprising a plurality of separate leaves which are relatively shiftable during the opening and closing movements of said springs. 90

5. In a draft-rigging, the combination with the draw-bar and its yoke, of two U-shaped springs, one of which is made flaring at its open end to receive the arms of the other spring, said springs each comprising a plurality of separate leaves which are relatively shiftable during the opening and closing movements of said spring, the leaves which make up each spring being made of varying lengths and the longer leaf of the inside spring being 100 located on the outside of said spring while the longer leaf of the larger or outside spring is located on the inner side of said spring to frictionally engage said outer longer leaf of the inner spring. 105

6. In a draft-rigging, the combination with a draw-bar, and its yoke, draft-plates, follower-bars extending through the yoke and engaging pockets in said draft-plates, of two U-shaped springs seated at their closed ends 110 against the follower-bars, one of said springs being made flaring at its open end to receive the arms of the other spring.

7. In a draft-rigging, the combination with a draw-bar, and its yoke, draft-plates, follower-bars extending through the yoke and engaging pockets in said draft-plates, of two U-shaped springs seated at their closed ends against the follower-bars, one of said springs being made flaring at its open end to receive 115 the arms of the other spring, each spring being made of a plurality of leaves which are relatively shiftable during the opening and closing movements of the springs. 120

8. In a draft-rigging, the combination with a draw-bar, and its yoke, draft-plates, follower-bars extending through the yoke and engaging pockets in said draft-plates, of two 125

U-shaped springs seated at their closed ends against the follower-bars, one of said springs being made flaring at its open end to receive the arms of the other spring, and a coiled spring located between the arms of the inner U-shaped spring and acting at its ends against the closed parts of said springs.

5 In testimony that I claim the foregoing as

my invention I affix my signature, in presence of two witnesses, this 20th day of June, A. D. 1903.

JAMES A. HINSON.
